(Cl. D81—19)

FIG. 1.

FIG. 2.

FIG. 3.

FIG. 4.

FIGURE 1 is a front elevational view of a space heater showing my new design, the rear being substantially plain.

FIG. 2 is a side elevational view thereof as seen from the left of FIG. 1;

FIG. 3 is a side elevational view thereof as seen from the right of FIG. 1;

FIG. 4 is a top plan view thereof.

The grille pattern is shown only on part of the areas in FIGS. 1 and 4. It is to be understood that they continue over the entire panel areas shown.

I claim:

The ornamental design for a space heater, substantially as shown and described.
